UNITED STATES PATENT OFFICE.

SIDNEY STOCKING, OF HERSCHER, ILLINOIS.

CIGAR LIGHTER.

Application filed October 19, 1921. Serial No. 508,768.

To all whom it may concern:

Be it known that I, SIDNEY STOCKING, a citizen of the United States, and a resident of Herscher, in the county of Kankakee, and State of Illinois, have invented a new and useful Improvement in Cigar Lighters, of which the following is a full, clear, and exact description.

My invention relates to cigar lighters, and it consists in the combinations, constructions and arrangements herein described and claimed.

An object of my invention is to provide a cigar lighter in which the gas used is cut off completely while the device is not in use.

A further object of my invention is to provide a device of the character described in which the electrical circuit for igniting the gas is broken when the device is not in use.

A further object of my invention is to provide a device of the character described having a gas valve and an electrical switch, both of which are operated simultaneously when the hand torch is removed or replaced on its hook.

A further object of my invention is to provide a device of the character described in which the size of the flame produced may be regulated.

A further object of my invention is to provide a device of the character described which is simple in operation and which is thoroughly effective for the purpose intended.

Other objects and advantages will appear in the following specification, and the novel features of the invention will be particularly pointed out in the appended claims.

My invention is illustrated in the accompanying drawings forming a part of this application, in which

Figure 1 is a plan view of my device with the cover removed,

Figure 2 is an end elevation of my device, Figure 3 is a sectional view of the hand torch,

Figure 4 is a plan view of the core member of the hand torch,

Figure 5 is a fragmentary sectional view of the core member,

Figure 6 is a fragmentary view of the gas valve partially in section, and

Figure 7 is a sectional view along the line 7—7 of Figure 6.

In carrying out my invention, I make use

of a box member 1 having a base 2 and side walls 3, 4, 5 and 6. A cover 7 is provided and may be removed by the loosening of screws 8.

Pivotedly mounted within the box 1 on a supporting arm 9 I provide a lever 10 having a bifurcated portion 11 similar to the ordinary telephone receiver hook. The portion 11 extends out of the box through an opening 12. A spring 13 is secured to the opposite end of the lever 10 at 14 and to the side wall 4 of the box. The purpose of the spring 13 is to move the lever 10 to the position shown in dotted lines unless otherwise held down.

A valve 15 is supported within the box 1 by means of a base 16 and is provided with a spindle 17. The spindle 17 has connected thereto a short lever arm 18. A link 19 is pivotally mounted at one end to the lever arm 18 and at its opposite end to the lever 10, as shown at 20. It will thus be seen that when the lever 10 is moved that the spindle of the valve 15 will turn. Referring now to Figures 6 and 7, the valve 15 consists of a valve casing 21 having two oppositely disposed ports 22 and 23. A rotatably mounted valve gate 24 is provided within the casing 21 and has a passage 25 therethrough, which passage is arranged to register with the ports 22 and 23. The valve gate 24 is arranged to turn with the spindle 17. A nut 26 is carried by a downwardly extending threaded portion of the valve gate 24 and provides a means for tightening the valve to insure against leakage.

A regulating valve 27 is carried by the side wall 5 and is connected directly to a gas supply, such as the illuminating gas in common use. The other port of the valve 27 is connected by means of a tube 29 to the port 23 of the valve 15. The purpose of the valve 27 is to regulate the amount of gas flowing from the source 28 to the valve 15.

Connected to the port 22 of the valve 15 is a flexible tube 30 which passes through an opening 31 in the side wall 4 and through a larger flexible tube 32 to the hand torch 33. Referring to Figure 3, the hand torch 33 comprises a tubular casing 34 of fibre or other suitable material, having disposed therein a core member 35. The core member 35 consists of a wooden spindle 36 having a central passage 37, one end of which is enlarged as shown at 38. A metal tube 39

is tightly fitted within the enlarged passage 38 and extends beyond the spindle 36. The tube 39 is provided at its outer end with a screen 40 having at one side thereof a rough contact plate 41. The contact plate 41 is electrically connected to the tube 39 by the screen 40. Secured to the outer surface of the spindle 36 is a spring conducting member 42 which extends beyond the end of the tube 39 and is bent over the end thereof as shown at 43 so that pressure on the spring member 42 would cause the bent portion 43 which bears a contact point 44 to make contact with the contact plate 41. The tube 30 extends up through the spindle 36 and is connected to the tube 39 so that when the valve 15 is opened, gas will flow up and out of the opening of the tube 39. The spindle 36 is provided also with passages 45 and 46 for the accommodation of wires 47 and 48. The wires 47 and 48 are connected to the contact member 42 and the tube 39 respectively and extend out from the spindle 36 and up through the flexible tube 32 and into the box 1.

Metal caps 49 and 50 are fixed at the end of the tubular casing 34. The cap 49 is provided with an annular opening 51 which is large enough to permit the entrance of a cigar or cigarette and allow free passage for the flame of the gas when ignited.

Means for igniting the gas at the screen 40 of the hand torch is provided in an induction coil 52, one terminal 53 of which is connected to a binding post 54 and the other terminal to a contact surface 55 which is secured to the base. A contact brush 56 is carried by the lever 10 and is connected to one of the two wires 47 or 48. The other wire 27 is connected to a binding post 57. The binding posts 54 and 57 are connected to a current source preferably to a direct current of low voltage. Means for manually moving the spring member 42 is provided in a button 58 disposed through the tubular casing 34. Pressure on the button 58 will cause the member 42 to move and make contact at 44 with the contact plate 41.

From the foregoing description of the various parts of the device, the operation thereof may be readily understood. The hand torch 33 is normally disposed upon the bifurcated hook portion 11 by the lever 10, thus the weight of the torch holds the lever 10 in the position shown in Figure 1. The contact brush 56 is away from the contact surface 55 and the circuit therethrough is broken. The lever arm 18 is in a position to cause the valve 15 to be shut off. This is clearly shown in Figure 7.

To operate the device or to make use of the device, the operator removes the hand torch 33 which causes the spring 18 to move

the lever 10 to the position shown in the dotted lines in Figure 1, the contact brush 56 making contact with the contact surface 55. The lever arm 18 of the valve 15 is moved and the valve 15 thus opens. The dotted lines in Figure 7 show the position of the valve gate at this time. Gas will now flow from the source 28 down through the valve 27, by way of the tube 29, through the valve 15 and the tube 30, up into the metal tube 39, and out through the screen 40. The thumb button 58 is at this time pressed back and forth so that the contact point 44 is moved to and away from the contact plate 41, making or breaking the circuit. An arc will occur at each break of the contact 44 from the plate 41. This arc would ignite the gas flowing out the tube 39 and a flame would be produced above the screen 40. The purpose of the screen 41 is to prevent the flame from receding into the tube and unduly heating the torch.

A cigar or cigarette can now be held at the opening 51 of the cap 49 and ignited.

When this operation is over, the hand torch is replaced on the hook 11 and the electrical circuit as well as the gas ignition is broken.

Should the flame be too high, the valve 27 may be regulated to reduce or increase the size of the flame.

I claim:

1. A device of the character described comprising a gas hand torch, a pivotally mounted lever for supporting said torch, means for conducting gas to said torch, means for electrically igniting said gas in said hand torch, a valve associated with said first named means and operatively connected to said lever, whereby said gas will be shut off when said lever is supporting said torch and whereby said gas will be turned on when said torch is removed from said lever, and a switch associated with said second named means and operatively connected with said lever, whereby said second named means is rendered inoperable when said lever is supporting said torch.

2. A hand gas torch comprising a tubular casing, a metal tube disposed within said casing, means for conducting gas to said tube, a screen over the mouth of said tube, a contact plate secured to said screen, a spring contact member insulated from said tube and arranged to make contact with said contact plate when pressure is brought to bear thereon, and a hood-shaped cap secured to said casing to shield the mouth of said tube, said contact members being arranged for connection with an electric current source.

SIDNEY STOCKING.
